SHOE

Chester D. Turner, Haverhill, Mass., assignor to
 United Shoe Machinery Corporation, Borough
 of Flemington, N. J., a corporation of New
 Jersey

Application January 4, 1938, Serial No. 183,333

1 Claim. (Cl. 36—12)

This invention relates to shoes and shoemaking and, more particularly, to improvements in the means and methods employed in securing cement attached tread soles.

5 All too frequently the adhesive bond securing the tread sole of such a shoe is ruptured or broken when the shoe is subjected to wearing strains, the strains imposed on the sole when the shoe is scuffed being transmitted directly to the cement bond seam. Such ruptures are very likely to occur if the inner surface of the tread sole is fleshy, the loose surface fibers held by the cement tearing away from the sole.

10 It is a principal object of my invention, therefore, to provide an improved shoe in which the cement bond securing the sole is strongly reinforced at the toe portion by invisible supplemental means securing the sole more permanently to the shoe. Another principal object is 15 to provide a simple and practical method of constructing shoes embodying my improvement, and other and further objects will appear from the following specification.

15 The invention will now be explained with reference to the accompanying drawing, in which:

Fig. 1 is a side elevation of the forepart of a lasted shoe having a cement attached extension sole prepared in accordance with my invention, the toe portion of the shoe being shown in cross-section;

20 Fig. 2 is a view similar to Fig. 1 disclosing the manner and means whereby the adhesive bond securing the sole is supplemented and reinforced;

25 Fig. 3 is a perspective view of the shoe in the same condition illustrated in Fig. 2 and clearly shows a preferred arrangement of supplementary metallic fasteners; and

30 Fig. 4 is another view similar to Fig. 1, disclosing the finished shoe.

35 In carrying out my improvement, the tread sole 10 of the shoe is split into two portions at the toe, an inner portion 11 and an integral outer portion or flap 12, the split preferably being effected before the sole is cemented to the shoe 40 and extending rearwardly from the toe end throughout the toe portion to the tip line. After attachment of the sole, the flap 12 is turned back, as shown in Figs. 2 and 3, and a plurality of metallic fasteners, such as staples or tacks 15, 45 are driven through the sole portion 11, the margin 16 of the upper, and the insole 17, and are clinched at their inner ends against a metal toe 50

plate 21 carried on the bottom of the last 20, the tacks or fasteners being preferably spaced and arranged about the toe portion of the shoe substantially as illustrated in Fig. 3. The outer portion or flap 12 is then restored and secured in its original relation to the portion 11, as by cement, thereby covering the tacks and rendering them invisible.

5 In order to provide a finished surface on the flesh side of the sole extension 18 in shoes of this type, and in order to reinforce the extension edge against curling, I prefer to apply a welt 22 over the edge, securing the welt in place by stitching 24 in the manner usual in applying welts to shoes of stitchdown construction, the stitches being aloft both on the welt and on the tread surface of the sole, as shown. Where this is done the stitching may be relied upon to secure the split portions of the sole together without recourse to the use of cement, except that an application of latex or other light adhesive will be found desirable for holding the flap in place preparatory to stitching the welt in position.

10 The remaining operations necessary to finish the shoe, including removal of the last, are performed in the usual manner.

15 In shoes thus constructed, the supplemental sole attaching means will be found to afford excellent reinforcement for the cement bond primarily relied upon to secure the outsole to the shoe, any tendency for the sole to tear loose being effectively resisted by the metallic fasteners.

20 Having thus described my invention, what I claim as new and desire to secure by Letters Patent of the United States is:

25 In a shoe having a cement attached extension sole, the improvement characterized by the sole being split rearwardly from the toe end to the tip line only to define an integral flap on the tread side thereof, a plurality of metallic fasteners extending through the remaining toe portion of the sole and through the cement into the shoe, 30 a welt overlying the edge extension of the sole, and a line of stitching extending through said welt, edge extension, and flap, to secure the welt and flap in position, the cement bond between the shoe and sole being solely relied upon to hold the shoe and sole together except at the toe portion where the metallic fasteners are inserted.

CHESTER D. TURNER.
